UNITED STATES PATENT OFFICE.

WALLACE HENRY PAULL, OF HAMPTON-IN-ARDEN, ENGLAND, ASSIGNOR TO DUNLOP
TIRE AND RUBBER CORPORATION OF AMERICA, A CORPORATION OF NEW YORK.

DESIGN FOR A TIRE TREAD.

Application filed March 29, 1923. Serial No. 5,639. Term of patent 14 years.

To all whom it may concern:

Be it known that I, WALLACE HENRY PAULL, a subject of the King of Great Britain, residing at Hampton-in-Arden, Warwickshire, England, have invented a new, original, and ornamental Design for Tire Treads, of which the following is a specification, reference being had to the accompanying drawing, forming a part thereof.

Fig. 1 is a sectional perspective view and Fig. 2 is a developed partial plan view of a tire showing my new design.

The drawings illustrate the design as applied to an ordinary pneumatic tire casing, but the invention is applicable to treads of other kinds of tires such, for example, as solid and semi-solid tires.

I claim:

The ornamental design for a tire tread as shown.

In witness whereof, I have hereunto signed my name.

WALLACE HENRY PAULL.
